UNITED STATES PATENT OFFICE.

CHARLES L. NORWOOD, OF PHILADELPHIA, PENNSYLVANIA.

ELECTRIC THERMOSTAT.

1,248,894.

Specification of Letters Patent. Patented Dec. 4, 1917.

Application filed May 2, 1917. Serial No. 165,904.

To all whom it may concern:

Be it known that I, CHARLES L. NORWOOD, a citizen of the United States, residing at Philadelphia, in the county of Philadelphia 5 and State of Pennsylvania, have invented certain new and useful Improvements in Electric Thermostats, of which the following is a specification.

The object of this invention is to supply 10 a long-felt need in the maintenance of substantially constant temperature and ventilation within a building.

More specifically the invention provides a most efficient thermostat for regulating 15 the amount of heat supplied to a given room or compartment, as well as automatically adjusting means for modifying the excessive heat therein in warm weather.

The object of the invention is further- 20 more to provide means for shutting off the heat supply as the temperature rises above a certain predetermined point, and shortly above said point to make effective a cooling medium, such as a refrigerating means, or 25 to simply turn on an electric fan.

And a further object is to provide an enclosure for the thermostat comprising the invention, which is both neat and attractive to the eye, and acts to protect the latter 30 from the effect of dust, dirt, or the like.

These and other objects of the invention, together with the details of the construction and operation thereof, are fully brought out in the accompanying drawings in which 35 Figure 1 is an elevational view of the preferred form of the device as secured to the wall surface of a room; Fig. 2 is a central vertical section of the same; Fig. 3 is an enlarged detail view showing the means for 40 forming the electrical connections of the circuits of the device; and Fig. 4 is a wiring diagram of the electrical circuits employed in the device forming this embodiment of the invention.

Referring to the drawings, the preferred 45 embodiment of the invention comprises a glass thermometer tube 1, having an enlarged reservoir 2 at one end, and partially filled with mercury 3, or other material 50 capable of relatively great contraction and expansion upon being subjected to changes in cold and heat intensities.

Resting upon the upper end of the said 55 mercury column is a pellet 4 of suitable insulating material, supporting in turn a

loosely fitting metallic cylinder 5, or short mercury column, which by virtue of the peculiar capillary characteristics of that metal will remain separated from the lower column, without tending to pass around the 60 said pellet, the true shapes of the neighboring surfaces of the two columns being substantially as shown.

The reservoir 2 of the tube is preferably supported by resilient arms 6 partially embracing the same, while the upper portion of the tube is held in upright position by means of resilient fingers 7, both of said arms and fingers being unitarily secured to the front wall of a casing 8, provided with 70 slanting side walls 9, and a vertically extending slot 10.

Also secured to the inner side surface of the said casing is a bar 11 upon which are slidably mounted a pair of sleeves 12, having pins 13 which pass outwardly through the said slot 10, and are capped with pointers 14, which indicate their positions vertically by means of the graduations 15.

The wall of the room in which the thermostat is located is provided behind the casing 8 with a yielding contact 16, which normally presses against a stud or contact member 17, sealed into the rear side of the tube 1. Also, each of the sleeves 12 is provided with a yielding contact member 18, adapted to carry current to sealed-in studs 85 or contact members 19 and 20 as the former slide over the latter successively.

With this construction, the two pointers 90 are set at the respective temperatures at which the apparatus is desired to operate, say for instance 75° and 70°. Then, when the temperature forces the mercury column and the upper superimposed cylinder in accordance with the heat of 75° or more, electric current passes through the wire 22, cylinder 5, one of the studs 19, neighboring contact 18 and sleeve 12, wire 23, fan 24 (or refrigerating system) and return 100 wire 25.

The temperature by this operation is indirectly forced downward until the cylinder 5 breaks the contact with the stud 19, and there remains between 70° and 75°. 105 However, if it continues below the former temperature, contact is made between the said cylinder and one of the contacts 20, thus completing the circuit through the wire 22, cylinder 5, stud 20, neighboring contact 110

18 and sleeve 12, wire 26 and heat-regulating valve 27 or the like, and wire 28, which eventually connects with the wire 25.

This invention may also be used to regulate the temperatures of vulcanizers, which is believed to be between 250° and 300°, as well as for breaking the charging current when in the operation of charging storage or secondary batteries the same become dangerously overheated.

Having thus described my invention, what I claim and desire to protect by Letters Patent of the United States is:—

A thermostatic circuit closer comprising a mercury tube, a metallic member actuated directly by the mercury column, and insulated therefrom, a contact sealed in the said tube and normally in contact with said mem-

ber, an upper and a lower series of contacts sealed in said tube and adapted to be 20 in contact with said member as it is moved by said column upon a change in temperature, a casing for said tube, means carried by said casing to support said tube, a rod carried by said casing, and electrical contacts 25 slidably carried by said rod and adapted to contact with the contacts of said series selectively upon predetermined changes in temperature.

In testimony whereof I have affixed my 30 signature in presence of two witnesses.

CHARLES L. NORWOOD.
